W. D. PORTER, OF PETERSBURG, VIRGINIA, ASSIGNOR TO HIMSELF AND
JAMES H. PLATT, JR., OF SAME PLACE.

Letters Patent No. 70,610, dated November 5, 1867.

TOY HUMMING-WHEEL.

The Schedule referred to in these Letters Patent and making part of the same.

TO ALL WHOM IT MAY CONCERN:

Be it known that I, W. D. PORTER, of Petersburg, in the county of Dinwiddie, and State of Virginia, have invented certain new and useful improvements in Toy Humming-Wheels; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in making a new and improved humming-wheel, to be used as a parlor toy, or for amusement generally. In the drawings—

Figure 1 is an edge view,

Figure 2 is a sectional view, and

Figure 3 is a side view.

In constructing my toy, I first cut out two circular pieces of tin or other metal, having a diameter of about three inches, and cut four holes in one of them, near its circumference or outer edge, placing two of them near each other, and on a line parallel with its circumference, and near the opposite ends of its radii, as shown in fig. 3. These circular pieces of tin or other metal I then form into disks A A', fig. 1, having an altitude of about one-twelfth ($\frac{1}{12}$) of their diameter, and unite them in any of the ordinary ways at their edges, and thus make a hollow wheel, E, with protruding or convex sides, as shown in figs. 1 and 2. Near the centres of the convex sides I fasten two eyes or loops *a a* so that they may be about one-quarter or one-half of an inch apart. Through these eyes or loops I pass cords B, and fasten their opposite ends to wooden handles C C, as shown in fig. 1.

In operating the wheel, I take the handles C C, one in each hand, and then whirl the wheel E until it has twisted the cords between it and the handles tightly together. I then pull the handles in opposite directions, which causes the wheel to turn rapidly, and, in turning, it gets sufficient momentum to twist the cords in the opposite direction. As it does this I move the handles nearer to each other, so that this twisting may be the more complete. I then pull the handles, as before, in opposite directions, and the wheel turns rapidly, as at first. This motion I can keep up for an indefinite length of time. The wheel, as it is revolved in this way, gives out a clear humming noise, to the great amusement and interest of the operator and bystanders.

As a parlor toy, it affords no end of amusement, and serves specially to interest children, who can operate it as readily as grown people. It may be made of different sizes, and with one, two, or more holes grouped together in one side, and may be made as ornamental as desired.

Having thus described my invention, what I claim, is—

The toy-wheel E, formed by the union of two concave disks, united at their peripheries, and provided with one or more openings D and the loops *a*, when said parts are constructed and arranged as herein shown and described.
